BEVIER VAN GORDER, OF NEW YORK, N. Y., ASSIGNOR TO WESER BROS. INC., OF NEW YORK, N. Y., A CORPORATION OF NEW YORK.

MECHANICAL MUSICAL INSTRUMENT.

Application filed January 7, 1924. Serial No. 684,717.

My invention relates generally to pneumatically operated musical instruments, such as player-pianos, organs and other musical instruments of the well-known type 5 in which a perforated music-sheet is caused to travel over a tracker-bar formed with a series of air-ducts connected with the playing devices, and my improvements relate more particularly to attachments used in 10 connection with the music-sheet winding and rewinding mechanism by which the instrument is operatively controlled, and especially with an improved alternately operating brake mechanism adapted to bear with 15 varying pressure on the surface of the music-sheet, which mechanism is thrown into, or out of, operative position according to the direction of the travel of the music-sheet.

20 It is well-known that in the ordinary player during the re-wind of the music-sheet from the take-up roll, the sheet moves with great rapidity and is more or less loosely wound on the music-roll, while the 25 metal ring at the end of the music-sheet, when disengaged from the take-up roll, rotates rapidly until the motor stops, with the likelihood that such ring will disfigure the inner surface of the tracker-box while causing 30 disagreeable slapping noises. Heretofore this loose winding and undesirable action of the end of the music-sheet have been prevented by placing the hand of the performer on the surface of the music-sheet 35 as it is wound back on its music-roll; this, however, is not always convenient and moreover soon soils or otherwise injures the outside surface of the roll.

40 The objects of my invention are, among other things, chiefly to provide a simple, efficient and automatic mechanism controlled by the variable pressure in the action wind-chest, which mechanism will be immediately thrown into action at the beginning 45 of the rewinding of the music-sheet and will thereafter continue in operation until after the forward end of the music-sheet has become disengaged from the catch on the take-up roll, thereby preventing undesirable 50 slapping noises while serving to wind the music-sheet tightly on its roll or spool.

A further purpose of my invention is that such improved mechanism bearing directly 55 on the surface of the travelling music-sheet

during the re-wind will automatically be placed in inoperative position directly as the motor ends its rewind and begins the forward winding in rendering the musical composition with the vacuum pressure on 60 the action wind-chest.

With the foregoing and other objects in view, the invention comprises the features of construction, the parts and combinations thereof and the mode of operation as hereinafter described and then particularly pointed out in the appended claims.

65 Of the drawings, Fig. 1 is a front elevation of a player-piano with parts broken out and the front casing removed showing 70 an embodiment of the invention somewhat in diagrammatic form;

Fig. 2 is a front view thereof on an enlarged scale;

Fig. 3 is a top plan view;

Fig. 4 is a rear elevation;

Fig. 5 is a sectional view taken on the line 5—5 of Fig. 2 showing the position of the parts at the beginning of the rewind of the music-sheet on the music-roll; and

Fig. 6 is a sectional view taken on the line 6—6 of Fig. 2 showing the pneumatic collapsed with the brake out of action during the forward travel of the sheet.

Similar numerals refer to similar parts 85 throughout the several figures.

Referring to the drawings, more particularly Fig. 1, the player-piano which is chosen for a preferred embodiment of the invention may be of any usual construction, comprising, so far as shown, the frame and supporting case 7, the tracker-box 8 with the tracker-bar 9 provided with the customary air-ducts 10 on its face. Journalled in the tracker box 8 are the take-up roll 11 and the music-roll 12, the latter carrying the music-sheet 13. Operatively connected with the take-up roll 11 and music-roll 12 is the gearing 14 driven from the motor 15 by the sprocket chain 16 in the usual manner. The 90 gearing 14 is shifted by the rewind lever 17 for winding and rewinding the music-sheet 13 in the customary manner, except as hereinafter explained, the present improvements not directly relating with the structural details, arrangement and operation of such devices.

100 As shown in Fig. 1, the rewind lever 17 is connected by the link 18 to the rock-shaft 19 which actuates the rod 20 to move the 105

clutch-shifting lever 21 by which the motor 15 is operatively connected with either the take-up roll 11 or with the music-roll driver for rewinding the music-sheet 13 from the 5 take-up roll 11 back onto the music-roll 12. The motor 15 is connected by the main wind-trunk 22 with the usual pumping bellows (not shown) to create the required exhaust or vacuum pressure used as the motive 10 power in the player-piano.

Referring more particularly to Figs. 2 to 6 inclusive, I have here shown a preferred form of the automatic brake mechanism for bearing on the surface of the music-sheet 13 during the rewind: To the rear-wall 23 extending across the back of the tracker-box 8 the bracket 24 is suitably secured; in this bracket 24 the transverse bolt 25 is journaled so as to freely rock therein. Depending 20 from the ends of bolt 25 are two spaced-apart rods 26 looped at their ends to carry the laterally-extending spool 27 freely rotatable on the rods 26. Secured to the middle of the bolt 25 and extending through the 25 opening 28 in the wall 23 is the downwardly bent arm 29 adapted to be engaged by the rock-lever 30 attached to the movable leaf 31 of the pneumatic 32 secured to the back of the rear-wall 23 as shown in Fig. 3. The 30 spring 33 secured to the leaf 31 and the body 34 of the pneumatic 32 normally tends to raise the hinged leaf 31 to its Fig. 3 position. The interior of the pneumatic 32 is connected by the nipple 35 and tube 36 to the 35 action wind-chest 37 (shown diagrammatically in Fig. 1), which wind-chest 37 is connected by tube 38 to the usual gate box on the pumping bellows (not shown), the rewind lever 17 also controlling the air or 40 exhaust pressure in the wind-chest 37 in the usual manner through connections with the rock-shaft 19 (not shown).

When the player action is rendering the musical composition by the forward travel 45 of the music-sheet 13 over the tracker-bar 9, the leaf 31 is held in its collapsed Fig. 6 position against the tension of the spring 33 with the end of the lever 30 disengaged from the arm 29 thereby allowing the spool 27 50 to fall downwardly by gravity and rest against the rear wall 23 away from the music-roll 12 and in inoperative position therewith. However, when the performer shifts the rewind lever 17 in the usual manner to cut off the action wind-chest 37 from 55 exhaust pressure while simultaneously shifting the gearing 14 to start the music roll rewind, the exhaust tension in the pneumatic 32 from the wind-chest 37 is immediately 60 broken and the leaf 31 is forced upwardly by the spring 33 which swings the lever 30 so that its free end moves forwardly against the arm 29 to press the brake spool 27 yielding 65 against the surface of the rear end of the music-sheet 13 as the latter begins its

rewind on its roll 12, all as shown in Fig. 5. As the thickness of the paper increases on the roll 12, the growing diameter of the revolving roll and music-sheet will force the 70 spool 27 rearwardly against the force of the spring 33 which reacts in turn to cause the spool 27 to bear against the surface of the rewound music-sheet 13 with a gradually increasing pressure as such sheet is being rewound on the roll 12. 75

Such yielding pressure is maintained by the spool 27 bearing anti-frictionally on the surface of the sheet until the forward end of the music-sheet is disengaged from the take-up roll; such pressure likewise prevents the usual metal ring in such forward end from undesirably slapping against the tracker-box 8 as it leaves the take-up roll 11. When the lever 17 is again shifted to secure the forward travel of the music-sheet 13, the exhaust pressure now produced in the wind chest 37 will collapse the pneumatic 32 against the tension of the spring 33 to its Fig. 6 position, and the braking spool 27 80 will instantly fall away from the music-roll 90 12 and rest against the rear-wall 23 of the tracker-box. 85

The foregoing construction shows a practical form of attachment embodying the principles of my invention, but various changes may be made in the structural details and arrangement of the parts without departing from the scope of my improvements and without sacrificing its chief advantages. 95

I claim as my invention:

1. In a mechanical musical instrument controlled by a perforated music-sheet, devices for winding and rewinding the music-sheet, and means held in inoperative position and out of contact with the sheet during the forward travel of the sheet, but automatically brought to bear on the music-sheet during the rewind. 105

2. In a mechanical musical instrument controlled by a perforated music-sheet, devices for winding and rewinding the music-sheet, and means held in inoperative position and out of contact with the sheet during the forward travel of the sheet, but brought by said rewinding devices to bear yieldingly on the music-sheet during the rewind. 110

3. In a mechanical musical instrument controlled by a perforated music-sheet, devices for winding and rewinding the music-sheet, and means held in inoperative position during the forward travel of the sheet to bear yieldingly on the music-sheet with increasing pressure as the sheet is being rewound. 115

4. In a mechanical musical instrument controlled by a perforated music-sheet, devices for winding and rewinding the music-sheet, and means comprising an anti-frictional brake held by gravity in inoperative position and out of contact with the sheet during the 120

130

forward travel of the sheet, but automatically brought to bear on the music-sheet during the rewind.

5. In a mechanical musical instrument controlled by a perforated music-sheet, devices for winding and rewinding the music-sheet, and means comprising an anti-frictional brake held in inoperative position during the forward travel of the sheet to bear on the music sheet with increasing pressure as the sheet is being rewound.

6. In a mechanical musical instrument controlled by a perforated music-sheet carried by a music-roll, devices for winding and rewinding the music-sheet, and means held out of contact with the sheet during its forward travel by a spring-tensioned pneumatic when held collapsed, but automatically brought to bear yieldingly on the music-sheet on said roll during the rewind by the spring in said pneumatic when the latter is released.

7. In a mechanical musical instrument controlled by a perforated music-sheet, the combination of a music-roll carrying said sheet, an actuating motor therefor, a wind-chest under exhaust pressure, a spring-tensioned pneumatic connected with the wind-chest, a brake held out of contact with the sheet during its forward travel by said pneumatic when held collapsed from the exhaust pressure from the wind-chest, but automatically brought to bear yieldingly on the music-sheet on said roll during the rewind by the spring in said pneumatic when the latter is expanded as the exhaust pressure is cut off from said wind-chest and pneumatic.

8. In a mechanical musical instrument controlled by a perforated music-sheet, the combination of a music-roll carrying said sheet, an actuating motor therefor, a wind-chest under exhaust pressure, a spring-tensioned pneumatic connected with the wind-chest, a brake held out of contact with the sheet during its forward travel by said pneumatic when held collapsed from the exhaust pressure from the wind-chest, but automatically brought to bear directly and yieldingly on the surface of the music-sheet on said roll during the rewind by the spring in said pneumatic when the latter is expanded as the exhaust pressure is cut off from said wind-chest and pneumatic.

9. In a mechanical musical instrument controlled by a perforated music-sheet, the combination of a music-roll carrying said sheet, an actuating motor therefor, a wind-chest under exhaust pressure, a spring-tensioned pneumatic connected with the wind-chest, a brake held out of contact with the sheet during its forward travel by said pneumatic when held collapsed from the exhaust pressure from the wind-chest, but automatically brought to bear yieldingly and with gradually increasing pressure on the music-sheet on said roll during the rewind by the spring in said pneumatic when the latter is expanded as the exhaust pressure is cut off from said wind-chest and pneumatic.

10. In a mechanical musical instrument controlled by a perforated music-sheet, the combination of a music-roll carrying said sheet, an actuating motor therefor, a wind-chest under exhaust pressure, a spring-tensioned pneumatic connected with the wind-chest, an anti-frictional brake held out of contact with the sheet during its forward travel by said pneumatic when held collapsed from the exhaust pressure from the wind-chest, but automatically brought to bear directly and yieldingly and with gradually increasing pressure on the surface of the music-sheet on said roll during the rewind by the spring in said pneumatic when the latter is expanded as the exhaust pressure is cut off from said wind-chest and pneumatic.

11. In a mechanical musical instrument controlled by a perforated music-sheet, a music-roll carrying said sheet and spring-pressed means for directly applying a gradually increasing pressure to the surface of the music-sheet on said roll through increased compression of said spring means by the increasing diameter of the sheet on said roll during the rewind.

12. In a mechanical musical instrument controlled by a perforated music-sheet, a music-roll carrying said sheet and spring-pressed means for directly applying a gradually increasing yielding pressure to the surface of the music-sheet on said roll through increased compression of said spring means by the increasing diameter of the sheet on said roll during the rewind.

BEVIER VAN GORDER.
